SANDPAPER HOLDER

Robley Hume Smith, The Dalles, Oreg.

Application July 1, 1944, Serial No. 543,125

1 Claim. (Cl. 51—187)

1

The object of this invention is to supply a satisfactory tool for holding sandpaper securely while being used to roughen or smooth surfaces, whatever the contour, that require recoating with enamel, varnish, paint or similar material.

A further object of this invention is the provision of a tool which does not overreach the flexible limitation of sandpaper by a thoughtless disregard of disrupting the cohesive strength in the union of grit, glue and paper incident to a too sharp a curve at the holders or to the use of serrated clamps.

A further object of this invention is to obtain greater economy in the use of sheet abrasive.

Other advantages will be apparent from the specification and drawings.

In the drawings:

Figure 1 is a perspective view of my new and improved sandpaper holder.

Figure 2 is a perspective view of one of an identical pair of sandpaper locking devices.

Figure 3 is a perspective view of one of several identical felt pads.

Figure 4 is a perspective view of one of several identical metal elements for helping to hold the felt pads in alignment.

Figure 5 is a perspective view of two main frame elements that, considered as a pair, or separately, are duplicated.

Figure 6 is a sectional view of the tool taken on line 6—6 of Figure 7.

Figure 7 is a plan view of the tool, partially broken away for convenience of illustration.

Figure 8 is a sectional view of the tool, taken on line 8—8 of Figure 7.

With regard to the drawings, as identified, they are to a certain extent freehand illustrations of the shapes, sizes and positions of the standardized or implement parts of the invention, hence said drawings are not altogether precise, nor intended to be any other than approximations—a principle, I would have it understood, suggestive of anticipated modifications within reason, of course, and in accord with the scope and spirit of my invention.

Figure 1 shows a complete embodiment of the tool loaded with sandpaper 16 and ready for use, comprising three divisions; namely, the handhold 24 (section 3) indicated in Figures 6 and 8, the pair of identical sandpaper locking devices 11 (section 2), one clearly illustrated in Figure 2, both indicated as emplaced in Figures 6, 7 and 8, and the sandpaper matrix (section 1) minus a numerical designation in the drawings but containing all the remaining parts and elements for

2

completing the tool, said sections described in detail hereinafter.

Section 1, the sandpaper matrix, in a general sense is composed of a dual series of light sheet metal units and resilient fabric units strung in alternation on a pair of rods 8 in a manner to be known as loose-fitting and tight-fitting, respectively. The metal units as shown in Figure 7, designated numerically as 1, 2 (implied in the break-away but shown in Figure 5), 5 and 6, while the fabric units are designated as 7 and 26, said dual units either metal or fabric easily recognized, independent of numerical notations, by a mere glance at the drawings shown as Figures 1, 3, 4, 5, 6, 7 and 8.

Moreover, section 1, the sandpaper matrix, in a specific sense, has its various parts and elements described in detail now, each in the order of its assemblage, starting with the metal strip 5,

20 Figure 1, known as a splint per se and shown as isolated in Figure 4 and meant to be placed (in the assemblage) in close contact with a fabric 7 as in Figure 3, said fabric known as a felt pad (being composed of twofold fourply pieces of

25 felt) sewed 7A for holding the folds together while punching the holes 9 and creating the curves at each end, said curves within the limit (by design) of the flexibility of the sandpaper for taking the said curves without a disruption of

30 grit, glue and paper, said splint per se helping to keep the felt pad in alignment, being aided in that function by having its lower line coincident, or practically so, with the broken line 7A, meaning close to, not upon the folds of the felt pad (glance at Figure 8 at the multiple folds of as

35 many felt pads for easy comprehension of the reference to folds). And now follows in the assemblage a fabric unit 26 consisting of a onefold twoply piece of felt (not exactly a preferable ma-

40 terial because of a war priority) known as a guardrail used as a protective appurtenance for avoiding the creation of a blemish from an abrupt inadvertent approach to surfaces that must not be scratched by sandpaper, citing chrome strips on

45 automobile bodies, for example. This guardrail 26 is a shallow border of felt adjacent to the lateral edges of the sandpaper 16. In making use of the guardrail, the operative needs definite instruction, for he might not even guess its significance or the method of using it to an advantage except for enlightenment to be given presently under the title "Using the tool."

Section 1 containing next in the order of assemblage a pair of main frame elements 1 and 2 shown in Figure 5 as isolated and in Figure 8 as

combined with other elements, each of said main frame elements 1 and 2 having along its rectilinear top line a ninety degree crimp with a depth the thickness of a felt pad, Figure 3, whereas, the said element 1, Figure 5, is provided with a pair of sawtooth crimps on its lower line, one at each end, by means of which, in combination with its own top line crimp and that of its fellow element, the elements 1 and 2 as shown in Figure 8 are held apart and parallel preventing thereby a possible pinching of the metal member 12 (see Figure 2) shown in Figures 7 and 8 as inserted between the top line crimps of the said main frame elements. In such a position, the metal member 12 must have a freedom of movement as the need requires and gets it as a shuttle in a pair of perfect races.

Let it be noted now that the main frame elements 1 and 2, Figure 8, are apparent splints, one on each side of a felt pad, each of said elements to be known as a resolved splint in the appended claim, as distinguished from a splint per se, Figure 4, so named, first, because its lower line has the form and the position, hence the function, of a splint per se, and because, second, the said main frame elements have other functions, as complements to counterparts, noted hereinafter in the novel act of combining instantly the three sections of the tool into an integrated whole. So far five units have been strung on the rods 8 and described. On the opposite side of the tool are duplicate units as shown in Figure 7 or 8 and in reverse making the original group and the duplicated group of units represent so called rights and lefts, as it were. Between said groups of units, as shown in the plan view of the tool, Figure 7, are by actual count ten fabric units 7 and nine metal units 5. The central metal unit 6 as shown in Figure 6 clearly illustrated as a ratchet plane 21 with its notches 28 and manifestly a complement, in duplicate, to its counterpart readily recognized as a pawl, completes the assemblage and, like the main frame elements, is to be known as a resolved splint also. But notice further in this section 1 that the top lines of the two opposite and duplicate main frame elements 2 are in an imaginary plane above the common level of the felt pads and the splints per se, allowance being made thereby for the needed space required by the bolthead 21 and its lock 22 as indicated in Figure 8, said bolthead locking device placed directly beneath the so-called shuttle member 12 inserted between the top line crimps of the two opposite pairs of main frame elements 1 and 2, shown likewise in Figure 8 and later amplified.

Section 2, an identical pair of sandpaper locking devices, shall be called a square-jawed mouth 11 with pendent lips 14 and 15, referring to one of the pair indicated in Figure 2. The lower jaw 12 is stationary; the upper jaw 13, movable. As illustrated, the mouth 11 is agape and held thus by a full length molecular spring pivoted at 13A accounting for the upward movement of jaw 13, while the use of the nuts 23 on the bolts 20 exhibits the force for a downward movement of the jaw which in moving describes an arc unhampered by the threads of the vertical bolts 20 inasmuch as the holes in said upper jaw through which the bolts 20 are thrust are large enough to permit the freedom of movement along the predetermined arc with no obstructive entanglement of the light sheet metal jaw in the troughs of the threads. The lips 14 and 15 are the sandpaper 16 holders as shown in Figure 6, said

holders having a twofold gripping value, one of which ascribed to a frictional contact of the sandpaper 16 with the lips 14 and 15 when the nuts 23 are tightened (always by the fingers, not a wrench, as in the case of all other nuts in the tool), the other gripping value ascribed to the curve of the clamps. But notice that the lips are pendent, meaning that they swing beyond the ends of the main frame elements 1 and 2. So, inasmuch as the jaws 12 and 13 straddle the upper opposite main frame elements 1 as shown in Figure 7, a thin sheet of sandpaper with its fine-bolted grit cannot be clamped securely, hence the need of the pendent lip and a secondary molecular spring in the upper jaw 13, said spring pivoted along the line of contact of the lower edge of parallelepiped figure (in the upper jaw) with the topmost main frame elements, a provision that solves the problem of clamping thin sandpaper. The lower jaw 12 described already in section 1 as a shuttle (though for a moment only) provided with proper races which are the crimps of the paired main frame elements 1 and 2 as shown in Figure 8, and denoted as a counterpart to a complement in section 1, has a molecular spring pivoted at the lines where the flanks of the jaw break away from the races as shown in Figure 7, said molecular spring determines the strength in the snap of the pawl into a ratchet notch 28 as shown in Figure 6 for holding section 1 to section 2, said flanks of the jaw when the nuts 10 are tightened on the rods 8 as shown to be done as yet in Figure 8, act as stabilizers of the tool when brought in close contact with the sides of the outer opposite main frame elements 1.

Underneath the lower jaw 12 of the mouth 11 as shown in Figure 8 is a bolthead locking device, one of an identical four in the tool, said locking device consisting of a rectangular strip 21 of light sheet metal bent to slip into the groove 22 of the bolthead for holding it fast when the nut 23 of the bolt 20 is used. The hole in the metal strip 21 has the diameter of the bolt 20, said strip with the bolt thrust through it is held close up to the jaw 12 through which the bolt protrudes in a tight fit and extends through the upper jaw 13 with the hole in it designedly loose-fitting, thence the bolt 20 is passed through a pearshaped hole 25, one of four and identical, in the shell-like handhold 24 indicated in the Figures 1 and 8, and shown finally with its end protruding for the reason that the said boltend, in company with three others of its kind, is to be known as a hitching post in the nature of a complement to a counterpart when section 2 is hitched to section 3.

Section 3, the handhold 24, with its position illustrated in Figures 1, 6 and 8, consisting of a rectangular piece of light sheet metal in the shape of a shell the whole of which forming a molecular spring pivoted on the boltends 20 next to the nuts 23 by means of four pearshaped holes created from overlapping circles, the smaller ends of such composite holes being semicircles having the diameter of the bolts 20, said molecular spring in all the illustrations is active, not inert, and therefore the force for holding the four semicircles jam against the troughs in the threads adjacent to the nuts 23 as illustrated and hereinafter described more fully when the molecular spring is inert at the moment for attaching the section 3 to section 2.

As to joining (or disjoining) the three sections of the tool into an integrated whole almost in a

flash, note Figure 7 in which the pair of sandpaper locking devices 11, known as section 2, are attached to the sandpaper matrix known as section 1. In separating section 2 from section 1, I loosen the nuts 10 on the rods 8 the least bit, first, an act for disengaging slightly the hold the outer main frame elements 1 at the opposite sides of the tool has on the flanks of the lower jaw 12 Figure 2 more clearly shown; second, I lift the pawl 13A, Figure 2, or shown more clearly in Figure 6 as occupying a notch 28 in the ratchet plane 27, and in the lift overcoming the force of a molecular spring located in the jaw 12 of the mouth 11; then, third, push the sandpaper locking device known as a smooth outward from the tool (or section 1) and off. In a reverse procedure the section 2 is back again, locked securely to section 1.

In Figure 1 the handhold 24 known as section three is fastened to the pair of sandpaper locking devices 11 known as section 2 which, in turn, is attached to the sandpaper matrix known as section 1. To remove the handhold 24 from the sandpaper locking devices 11, take hold of the shell at its sides, exert a lateral pressure on the shell until the larger ends of the pear-shaped holes 25 swap places with the smaller semicircular ends which the molecular spring held tight in the troughs of the threaded bolt-ends and jam against the nuts 23. Having brought the shell into that position, lift it off, whereupon the molecular spring is inert. To replace the handhold, then, reverse the procedure; that is, exert a lateral pressure on the shell, having brought it into a position in which the composite holes 25 are above the boltends 20, until the larger ends of the composite holes 25 are directly above, or nearly so, the boltends 20, and while in that new position above the metal shell down and jam against the nuts 23 as in Figure 8. Now release the molecular spring. Thereupon, the metal shell takes hold of section 2 in a semicircular grasp and holds fast to its assigned troughs.

In loading the tool with sandpaper 16, first remove the handhold to get at the nuts 23. Figure 6 indicates that the sandpaper is loaded already, but imagine that the lips 14 and 15, between which the sandpaper is shown, are open. Then above the one end of sandpaper 16 between the lips 14 and 15 up against the bolts 20 which are called endstops, thereupon tighten the nuts 23 slightly, relying largely on a mere frictional engagement of the sandpaper with the lips for a momentary clasp—a tenuous hold—and after that procedure the sandpaper is brought to the second clasp at the opposite end of the tool, having kept the lateral edges of the paper parallel to the so-called guardrail of felt while placing the unattached end of the paper between the second pair of lips 14 and 15 (endstops not of use here) and making the paper fast by tightening the nuts 23, thereafter loosening the nuts

at the opposite end of the tool and taking up the slack in the paper for a final fastening, using fingers.

Take note that the lips 14 and 15 are curved and represent arcs that are a prolongation of the original arcs shown at the ends of feltpads over which the sandpaper is passed, in being loaded and used, with no sign of having reached, disastrously, beyond the limitation of flexibility.

10 In using the tool bear in mind that the sandpaper has a background of several folds of felt, said folds resembling nodes and loops, said loops equivalent to waves the crests of which bring manifold lines of sandpaper to bear on the surface to be abraded, whether the tool in use moves in transverse, oblique or horizontal directions. The idea is to multiply the cutting lines of the sandpaper indefinitely, consuming its entire value available, except the remnants in the clamps, said remnants being used later in the miniature tools each known as an individual sandpaper locking device, Figure 2. In feather edging use the curved ends of the tool as a means of avoiding too large a range of feather edging with a consequent waste of abrasive material. In using the guardrail of felt as a protective appurtenance for saving strips of chrome ornamentation, for example, from incautious scratches, bring the lateral side of the tool close to the ornament, press down on the tool and slide it, tilted, close up to the ornament. Such a maneuver forces the guardrail under the sandpaper at its edge, permitting necessary abrading close to the strip—and no harm done from scratching.

Having given a detailed description of my invention, supplemented by drawings, what I claim is:

40 A device of the class described comprising a body member having curved ends and being adapted to support a strip of abrasive material, said body member consisting of a plurality of layers of felt and narrow metal reinforcing strips interleaved between the felt layers adapted to reinforce and stiffen the felt layers, narrow side members on each longitudinal side having right angle beads formed at the tops thereof and extending partly across the top of the body member, spring jaw member at each end of the body member having flange members extending beneath the beads on the side members and clamped to the body member thereby, means engaging the jaw members to force the gripping of the jaw members together, a pair of felt guard rails along 45 each longitudinal side of the body member and extending beyond the abrasive supporting face thereof, bolt members adjacent each end of the body member passing through the side rails and body securely clamping the rails and body members together and a strip of abrasive material having each end clamped in a jaw member and being snugly supported by the body member.

ROBLEY HUME SMITH.
